UNITED STATES PATENT OFFICE.

LOUIS G. PACENT, OF WINFIELD, NEW YORK, ASSIGNOR TO PACENT ELECTRIC COMPANY, INC., OF NEW YORK, N. Y., A CORPORATION OF NEW YORK.

CONNECTING PLUG.

Application filed March 20, 1923. Serial No. 626,285.

To all whom it may concern:

Be it known that I, LOUIS G. PACENT, a citizen of the United States, residing at Winfield, in the county of Queens, State of New York, have invented certain new and useful Improvements in Connecting Plugs; and I do hereby declare the following to be a full, clear, and exact description of the invention, such as will enable others skilled in the art to which it appertains to make and use the same.

This invention has to do with connecting plugs, and, more particularly, telephone plugs. Its object is to provide a very simple and inexpensive connecting plug which is adapted to be readily connected to the terminals of a telephone cord of the kind provided with pin type cord tips.

At the present time the invention finds its most important embodiment in telephone plugs for use in conjunction with radio apparatus. Radio telephone head-sets are ordinarily provided with conductor cords having so-called pin type cord tips which of course are not adapted for making connections with spring jacks, but are particularly well adapted for making connections with certain types of binding posts and spring clips, such as the well-known Fahnestock clips. Because of the fact that it is frequently desirable to connect a telephone head-set with binding posts and the like, especially for experimental and testing purposes, it is undesirable in many cases to have the headset permanently connected to the plug. The structure of the present invention is designed to meet this situation in that it provides a plug to which a cord provided with the usual pin type cord tips can be quickly and easily connected and disconnected and in which the entire mechanism for effecting such connections is mounted inside the handle of the plug.

In connection with the detailed description of the invention to follow, reference is made to the accompanying drawing, in which—

Fig. 1 is an exterior elevational view illustrating the preferred embodiment of the invention;

Fig. 2 is a side elevation of the same plug;

Fig. 3 is an elevational view with one-half of the plug handle removed in order to more clearly disclose the interior structure;

Fig. 4 is an elevational view partly in

cross section of the plug with the handle removed illustrating the first step in the operation of connecting the telephone cords to the plug; and

Fig. 5 is a cross sectional view taken along the line 5—5 of Fig. 3.

The illustrated embodiment of the invention comprises a contact member 1 consisting of a tip 2 and sleeve 3 insulated from each other by means of suitable insulating bushings and washers. The tip 2 is connected to the end of a threaded stud 4, which extends through the sleeve 3 and is provided at its end with a nut 5. A pair of curved resilient members 6 and 7 are connected respectively to the sleeve 3 and stud 4, the latter being connected with the tip 2. The resilient members 6 and 7 normally assume the form indicated in Fig. 4, and the free end portion of each of these members is provided with an aperture of suitable size to permit the insertion therein of a pin type cord tip 8. The handle of the plug is preferably molded of a suitable insulating material such as hard rubber or a phenolic condensation product, and consists of two identical portions 9 and 10, which fit together and form a chamber for containing the resilient members 6 and 7, as is best illustrated in Fig. 3. The two parts of the handle are secured together by means of a screw 12.

In connecting the telephone cord to the plug, the cord tips are inserted in the apertures in the resilient members 6 and 7, as shown in Fig. 4, after which they are twisted into the position shown in Fig. 3, thereby flexing the resilient members. One of the portions of the handle such as 9 may then be put in place with the cord tips seated in the grooves provided for them, as is clearly illustrated in Fig. 3. The other half of the handle 10 may then be put in place and the two parts screwed together. The resilient members 6 and 7 being under considerable tension, the cord tips are securely gripped by the edges of the apertures in the resilient members through which they extend. Any force applied tending to withdraw the cord tips from the plug only tends to increase the gripping action of the resilient members 6 and 7 thereon, and it is quite impossible to remove the cord tips without removing the handle. This, however, is a very easy thing to do, since it requires only the removal of a single screw. When the two parts of

the handle are assembled together they, of course, form the apertures through which the telephone cords extend.

I claim:

5. 1. In a connecting plug, a contact member, a handle attached to said contact member, a resilient conducting member connected with said contact member, said resilient member having an apertured free end portion adapted to engage a pin type cord tip, said handle defining a chamber enclosing said resilient member, and an aperture adapted for the insertion of a pin type cord tip, said resilient member being adapted to 15 grip said cord tip and force it against the side of said aperture.
2. In a connecting plug, a contact member, a handle for said contact member, a resilient member having one end portion 20 attached to said contact member and its free end apertured to receive a pin type cord tip, the arrangement being such that the attachment of the cord tip to the resilient member is adapted to be effected by inserting the 25 cord tip into the aperture in said member and turning the cord tip into a predetermined position, thereby bending said resilient member and effecting a gripping action between said resilient member and said cord 30 tip, said handle being adapted to hold the cord tip in the said predetermined position.
3. In a connecting plug, a contact member, a two-part handle for said contact member, a resilient member having one end portion 35 attached to said contact member and its free end apertured to receive a pin type cord tip, said resilient member being adapted to be enclosed within said handle, the arrangement being such that the attachment 40 of the cord tip to the resilient member is adapted to be effected by inserting the cord tip into the aperture in said member and then turning the cord tip into a predetermined position, thereby flexing said resilient member and effecting a gripping action between said resilient member and said cord 45

tip, said handle being adapted to hold the cord tip in said predetermined position.

4. In a connecting plug, a contact member comprising a pair of contact elements, a pair of resilient conducting members attached to said contact elements respectively, said resilient members each being apertured at their free end portions to receive a pin type cord tip, a two-part handle adapted to be secured to said contact member, said handle, when assembled, defining a pair of apertures into each of which a conductor terminating in a cord tip may be inserted, the arrangement being such that the cord 55 tips may be securely attached to said resilient member by being first inserted in the apertures therein and afterward being turned in a predetermined position, the resilient members being flexed by the turning of the cord tips, said handle being adapted to hold the cord tips in the said predetermined position, thereby maintaining the gripping engagement between said resilient members and the cord tip. 60

5. In a connecting plug, a contact member, a resilient conducting member connected to said contact member, said resilient member having U-shaped portion the free end of which is provided with an aperture of a suitable size to permit the insertion therein of a pin type cord tip, the arrangement being such that by turning the cord tip after insertion into the said aperture said resilient member may be flexed 75 and a gripping engagement may be thereby effected between said resilient member and the cord tip, a two-part handle attached to said contact member, the two parts of said handle, when assembled together, defining a chamber in which said resilient member is enclosed, said handle being adapted to hold the cord tip in a position wherein it continues to be gripped by said resilient member. 80

In testimony whereof I affix my signature.
LOUIS G. PACENT. 85 90
